(57) **CLAIM**

The ornamental design for an insert shoelace buckle, as shown and described.

DESCRIPTION

FIG. 1 is a top perspective view of an insert shoelace buckle design showing my new design.

FIG. 2 is a bottom perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof; and,

FIG. 9 is a perspective view of the insert shoelace buckle where the insert shoelace buckle is in a configuration of use. The evenly dashed dotted lines in the figures show non-claimed features of the insert shoelace buckle and do not form part of the claimed design.
